CLAIM

The ornamental design for a back pack, as shown and described.

DESCRIPTION

FIG. 1 is a perspective view of a first embodiment of a back pack with the text of ARIZONA ARI, showing our new design;

FIG. 2 is a front elevational view corresponding to FIG. 1; FIG. 3 is a rear elevational view corresponding to FIG. 1; FIG. 4 is a bottom elevational view corresponding to FIG. 1; FIG. 5 is a top elevational view corresponding to FIG. 1; FIG. 6 is a left side elevational view corresponding to FIG. 1;

FIG. 7 is a right side elevational view corresponding to FIG. 1;

FIG. 8 is a perspective view of a second embodiment of a back pack with the text of ATLANTA ATL, showing our new design;

FIG. 9 is a front elevational view corresponding to FIG. 8; FIG. 10 is a rear elevational view corresponding to FIG. 8; FIG. 11 is a bottom elevational view corresponding to FIG. 8;

FIG. 12 is a top elevational view corresponding to FIG. 8; FIG. 13 is a left side elevational view corresponding to FIG. 8;

FIG. 14 is a right side elevational view corresponding to FIG. 8;

FIG. 15 is a perspective view of a third embodiment of a back pack with the text of BOSTON CITY, showing our new design;

FIG. 16 is a front elevational view corresponding to FIG. 15; FIG. 17 is a rear elevational view corresponding to FIG. 15; FIG. 18 is a bottom elevational view corresponding to FIG. 15;

FIG. 19 is a top elevational view corresponding to FIG. 15; FIG. 20 is a left side elevational view corresponding to FIG. 15;

FIG. 21 is a right side elevational view corresponding to FIG. 15;

FIG. 22 is a perspective view of a fourth embodiment of a back pack with the text of CALIFORNIA, showing our new design;

FIG. 23 is a front elevational view corresponding to FIG. 22; FIG. 24 is a rear elevational view corresponding to FIG. 22; FIG. 25 is a bottom elevational view corresponding to FIG. 22;

FIG. 26 is a top elevational view corresponding to FIG. 22; FIG. 27 is a left side elevational view corresponding to FIG. 22;

FIG. 28 is a right side elevational view corresponding to FIG. 22;

FIG. 29 is a perspective view of a fifth embodiment of a back pack with the text of CHARLESTON, showing our new design;

FIG. 30 is a front elevational view corresponding to FIG. 29; FIG. 31 is a rear elevational view corresponding to FIG. 29; FIG. 32 is a bottom elevational view corresponding to FIG. 29;

FIG. 33 is a top elevational view corresponding to FIG. 29; FIG. 34 is a left side elevational view corresponding to FIG. 29;

FIG. 35 is a right side elevational view corresponding to FIG. 29;

FIG. 36 is a perspective view of a sixth embodiment of a back pack with the text of CHARLOTTE, showing our new design;

FIG. 37 is a front elevational view corresponding to FIG. 36; FIG. 38 is a rear elevational view corresponding to FIG. 36; FIG. 39 is a bottom elevational view corresponding to FIG. 36;

FIG. 40 is a top elevational view corresponding to FIG. 36; FIG. 41 is a left side elevational view corresponding to FIG. 36;

FIG. 42 is a right side elevational view corresponding to FIG. 36;

FIG. 43 is a perspective view of a seventh embodiment of a back pack with the text of CHICAGO CITY, showing our new design;

FIG. 44 is a front elevational view corresponding to FIG. 43; FIG. 45 is a rear elevational view corresponding to FIG. 43; FIG. 46 is a bottom elevational view corresponding to FIG. 43;

FIG. 47 is a top elevational view corresponding to FIG. 43; FIG. 48 is a left side elevational view corresponding to FIG. 43;

FIG. 49 is a right side elevational view corresponding to FIG. 43;

FIG. 50 is a perspective view of a eighth embodiment of a back pack with the text of COLORADO COLO, showing our new design;

FIG. 51 is a front elevational view corresponding to FIG. 50; FIG. 52 is a rear elevational view corresponding to FIG. 50;

FIG. 53 is a bottom elevational view corresponding to FIG. 50;

FIG. 54 is a top elevational view corresponding to FIG. 50; FIG. 55 is a left side elevational view corresponding to FIG. 50;

FIG. 56 is a right side elevational view corresponding to FIG. 50;

FIG. 57 is a perspective view of a ninth embodiment of a back pack with the text of DALLAS DAL, showing our new design;

FIG. 58 is a front elevational view corresponding to FIG. 57; FIG. 59 is a rear elevational view corresponding to FIG. 57; FIG. 60 is a bottom elevational view corresponding to FIG. 57;

FIG. 61 is a top elevational view corresponding to FIG. 57; FIG. 62 is a left side elevational view corresponding to FIG. 57;

FIG. 63 is a right side elevational view corresponding to FIG. 57;

FIG. 64 is a perspective view of a tenth embodiment of a back pack with the text of DENVER DEN, showing our new design;

FIG. 65 is a front elevational view corresponding to FIG. 64; FIG. 66 is a rear elevational view corresponding to FIG. 64; FIG. 67 is a bottom elevational view corresponding to FIG. 64;

FIG. 68 is a top elevational view corresponding to FIG. 64; FIG. 69 is a left side elevational view corresponding to FIG. 64;

FIG. 70 is a right side elevational view corresponding to FIG. 64;

FIG. 71 is a perspective view of a eleventh embodiment of a back pack with the text of DESTIN DES, showing our new design;

FIG. 72 is a front elevational view corresponding to FIG. 71; FIG. 73 is a rear elevational view corresponding to FIG. 71; FIG. 74 is a bottom elevational view corresponding to FIG. 71;

FIG. 75 is a top elevational view corresponding to FIG. 71; FIG. 76 is a left side elevational view corresponding to FIG. 71;

FIG. 77 is a right side elevational view corresponding to FIG. 71;

FIG. 78 is a perspective view of a twelfth embodiment of a back pack with the text of DETROIT CITY, showing our new design;

FIG. 79 is a front elevational view corresponding to FIG. 78; FIG. 80 is a rear elevational view corresponding to FIG. 78; FIG. 81 is a bottom elevational view corresponding to FIG. 78;

FIG. 82 is a top elevational view corresponding to FIG. 78; FIG. 83 is a left side elevational view corresponding to FIG. 78;

FIG. 84 is a right side elevational view corresponding to FIG. 78;

FIG. 85 is a perspective view of a thirteenth embodiment of a back pack with the text of FLORIDA LOVE, showing our new design;

FIG. 86 is a front elevational view corresponding to FIG. 85; FIG. 87 is a rear elevational view corresponding to FIG. 85; FIG. 88 is a bottom elevational view corresponding to FIG. 85;

FIG. 89 is a top elevational view corresponding to FIG. 85; FIG. 90 is a left side elevational view corresponding to FIG. 85;

FIG. 91 is a right side elevational view corresponding to FIG. 85;
FIG. 92 is a perspective view of a fourteenth embodiment of a back pack with the text of GUAM LOVE GUAM, showing our new design;
FIG. 93 is a front elevational view corresponding to FIG. 92;
FIG. 94 is a rear elevational view corresponding to FIG. 92;
FIG. 95 is a bottom elevational view corresponding to FIG. 92;
FIG. 96 is a top elevational view corresponding to FIG. 92;
FIG. 97 is a left side elevational view corresponding to FIG. 92;
FIG. 98 is a right side elevational view corresponding to FIG. 92;
FIG. 99 is a perspective view of a fifteenth embodiment of a back pack with the text of HAWAII HA, showing our new design;
FIG. 100 is a front elevational view corresponding to FIG. 99;
FIG. 101 is a rear elevational view corresponding to FIG. 99;
FIG. 102 is a bottom elevational view corresponding to FIG. 99;
FIG. 103 is a top elevational view corresponding to FIG. 99;
FIG. 104 is a left side elevational view corresponding to FIG. 99;
FIG. 105 is a right side elevational view corresponding to FIG. 99;
FIG. 106 is a perspective view of a sixteenth embodiment of a back pack with the text of HONOLULU HONO, showing our new design;
FIG. 107 is a front elevational view corresponding to FIG. 106;
FIG. 108 is a rear elevational view corresponding to FIG. 106;
FIG. 109 is a bottom elevational view corresponding to FIG. 106;
FIG. 110 is a top elevational view corresponding to FIG. 106;
FIG. 111 is a left side elevational view corresponding to FIG. 106;
FIG. 112 is a right side elevational view corresponding to FIG. 106;
FIG. 113 is a perspective view of a seventeenth embodiment of a back pack with the text of HOUSTON HOU, showing our new design;
FIG. 114 is a front elevational view corresponding to FIG. 113;
FIG. 115 is a rear elevational view corresponding to FIG. 113;
FIG. 116 is a bottom elevational view corresponding to FIG. 113;
FIG. 117 is a top elevational view corresponding to FIG. 113;
FIG. 118 is a left side elevational view corresponding to FIG. 113;
FIG. 119 is a right side elevational view corresponding to FIG. 113;
FIG. 120 is a perspective view of an eighteenth embodiment of a back pack with the text of KEY WEST LOVE, showing our new design;
FIG. 121 is a front elevational view corresponding to FIG. 120;
FIG. 122 is a rear elevational view corresponding to FIG. 120;

FIG. 123 is a bottom elevational view corresponding to FIG. 120;
FIG. 124 is a top elevational view corresponding to FIG. 120;
FIG. 125 is a left side elevational view corresponding to FIG. 120;
FIG. 126 is a right side elevational view corresponding to FIG. 120;
FIG. 127 is a perspective view of a nineteenth embodiment of a back pack with the text of VIVA LAS VEGAS, showing our new design;
FIG. 128 is a front elevational view corresponding to FIG. 127;
FIG. 129 is a rear elevational view corresponding to FIG. 127;
FIG. 130 is a bottom elevational view corresponding to FIG. 127;
FIG. 131 is a top elevational view corresponding to FIG. 127;
FIG. 132 is a left side elevational view corresponding to FIG. 127;
FIG. 133 is a right side elevational view corresponding to FIG. 127;
FIG. 134 is a perspective view of a twentieth embodiment of a back pack with the text of LOS ANGESES, showing our new design;
FIG. 135 is a front elevational view corresponding to FIG. 134;
FIG. 136 is a rear elevational view corresponding to FIG. 134;
FIG. 137 is a bottom elevational view corresponding to FIG. 134;
FIG. 138 is a top elevational view corresponding to FIG. 134;
FIG. 139 is a left side elevational view corresponding to FIG. 134;
FIG. 140 is a right side elevational view corresponding to FIG. 134;
FIG. 141 is a perspective view of a twenty first embodiment of a back pack with the text of MAUI LOVE MAUI, showing our new design;
FIG. 142 is a front elevational view corresponding to FIG. 141;
FIG. 143 is a rear elevational view corresponding to FIG. 141;
FIG. 144 is a bottom elevational view corresponding to FIG. 141;
FIG. 145 is a top elevational view corresponding to FIG. 141;
FIG. 146 is a left side elevational view corresponding to FIG. 141;
FIG. 147 is a right side elevational view corresponding to FIG. 141;
FIG. 148 is a perspective view of a twenty second embodiment of a back pack with the text of MIAMI LOVE, showing our new design;
FIG. 149 is a front elevational view corresponding to FIG. 148;
FIG. 150 is a rear elevational view corresponding to FIG. 148;
FIG. 151 is a bottom elevational view corresponding to FIG. 148;
FIG. 152 is a top elevational view corresponding to FIG. 148;

FIG. 153 is a left side elevational view corresponding to FIG. 148;
FIG. 154 is a right side elevational view corresponding to FIG. 148;
FIG. 155 is a perspective view of a twenty third embodiment of a back pack with the text of MICHIGAN CITY, showing our new design;
FIG. 156 is a front elevational view corresponding to FIG. 155;
FIG. 157 is a rear elevational view corresponding to FIG. 155;
FIG. 158 is a bottom elevational view corresponding to FIG. 155;
FIG. 159 is a top elevational view corresponding to FIG. 155;
FIG. 160 is a left side elevational view corresponding to FIG. 155;
FIG. 161 is a right side elevational view corresponding to FIG. 155;
FIG. 162 is a perspective view of a twenty fourth embodiment of a back pack with the text of NEW ORLEANS, showing our new design;
FIG. 163 is a front elevational view corresponding to FIG. 162;
FIG. 164 is a rear elevational view corresponding to FIG. 162;
FIG. 165 is a bottom elevational view corresponding to FIG. 162;
FIG. 166 is a top elevational view corresponding to FIG. 162;
FIG. 167 is a left side elevational view corresponding to FIG. 162;
FIG. 168 is a right side elevational view corresponding to FIG. 162;
FIG. 169 is a perspective view of a twenty fifth embodiment of a back pack with the text of NEW YORK CITY, showing our new design;
FIG. 170 is a front elevational view corresponding to FIG. 169;
FIG. 171 is a rear elevational view corresponding to FIG. 169;
FIG. 172 is a bottom elevational view corresponding to FIG. 169;
FIG. 173 is a top elevational view corresponding to FIG. 169;
FIG. 174 is a left side elevational view corresponding to FIG. 169;
FIG. 175 is a right side elevational view corresponding to FIG. 169;
FIG. 176 is a perspective view of a twenty sixth embodiment of a back pack with the text of NORTH CAROLINA, showing our new design;
FIG. 177 is a front elevational view corresponding to FIG. 176;
FIG. 178 is a rear elevational view corresponding to FIG. 176;
FIG. 179 is a bottom elevational view corresponding to FIG. 176;
FIG. 180 is a top elevational view corresponding to FIG. 176;
FIG. 181 is a left side elevational view corresponding to FIG. 176;
FIG. 182 is a right side elevational view corresponding to FIG. 176;

FIG. 183 is a perspective view of a twenty seventh embodiment of a back pack with the text of ORLANDO CITY, showing our new design;
FIG. 184 is a front elevational view corresponding to FIG. 183;
FIG. 185 is a rear elevational view corresponding to FIG. 183;
FIG. 186 is a bottom elevational view corresponding to FIG. 183;
FIG. 187 is a top elevational view corresponding to FIG. 183;
FIG. 188 is a left side elevational view corresponding to FIG. 183;
FIG. 189 is a right side elevational view corresponding to FIG. 183;
FIG. 190 is a perspective view of a twenty eighth embodiment of a back pack with the text of PANAMA CITY BEACH, showing our new design;
FIG. 191 is a front elevational view corresponding to FIG. 190;
FIG. 192 is a rear elevational view corresponding to FIG. 190;
FIG. 193 is a bottom elevational view corresponding to FIG. 190;
FIG. 194 is a top elevational view corresponding to FIG. 190;
FIG. 195 is a left side elevational view corresponding to FIG. 190;
FIG. 196 is a right side elevational view corresponding to FIG. 190;
FIG. 197 is a perspective view of a twenty ninth embodiment of a back pack with the text of PHILADELPHIA, showing our new design;
FIG. 198 is a front elevational view corresponding to FIG. 197;
FIG. 199 is a rear elevational view corresponding to FIG. 197;
FIG. 200 is a bottom elevational view corresponding to FIG. 197;
FIG. 201 is a top elevational view corresponding to FIG. 197;
FIG. 202 is a left side elevational view corresponding to FIG. 197;
FIG. 203 is a right side elevational view corresponding to FIG. 197;
FIG. 204 is a perspective view of a thirtieth embodiment of a back pack with the text of PUERTO RICO, showing our new design;
FIG. 205 is a front elevational view corresponding to FIG. 204;
FIG. 206 is a rear elevational view corresponding to FIG. 204;
FIG. 207 is a bottom elevational view corresponding to FIG. 204;
FIG. 208 is a top elevational view corresponding to FIG. 204;
FIG. 209 is a left side elevational view corresponding to FIG. 204;
FIG. 210 is a right side elevational view corresponding to FIG. 204;
FIG. 211 is a perspective view of a thirty first embodiment of a back pack with the text of SAIPAN LOVE, showing our new design;
FIG. 212 is a front elevational view corresponding to FIG. 211;

FIG. 213 is a rear elevational view corresponding to FIG. 211;
FIG. 214 is a bottom elevational view corresponding to FIG. 211;
FIG. 215 is a top elevational view corresponding to FIG. 211;
FIG. 216 is a left side elevational view corresponding to FIG. 211;
FIG. 217 is a right side elevational view corresponding to FIG. 211;
FIG. 218 is a perspective view of a thirty second embodiment of a back pack with the text of SALT LAKE CITY, showing our new design;
FIG. 219 is a front elevational view corresponding to FIG. 218;
FIG. 220 is a rear elevational view corresponding to FIG. 218;
FIG. 221 is a bottom elevational view corresponding to FIG. 218;
FIG. 222 is a top elevational view corresponding to FIG. 218;
FIG. 223 is a left side elevational view corresponding to FIG. 218;
FIG. 224 is a right side elevational view corresponding to FIG. 218;
FIG. 225 is a perspective view of a thirty third embodiment of a back pack with the text of SAN ANTONIO, showing our new design;
FIG. 226 is a front elevational view corresponding to FIG. 225;
FIG. 227 is a rear elevational view corresponding to FIG. 225;
FIG. 228 is a bottom elevational view corresponding to FIG. 225;
FIG. 229 is a top elevational view corresponding to FIG. 225;
FIG. 230 is a left side elevational view corresponding to FIG. 225;
FIG. 231 is a right side elevational view corresponding to FIG. 225;
FIG. 232 is a perspective view of a thirty fourth embodiment of a back pack with the text of SAN DIEGO CITY, showing our new design;
FIG. 233 is a front elevational view corresponding to FIG. 232;
FIG. 234 is a rear elevational view corresponding to FIG. 232;
FIG. 235 is a bottom elevational view corresponding to FIG. 232;
FIG. 236 is a top elevational view corresponding to FIG. 232;
FIG. 237 is a left side elevational view corresponding to FIG. 232;
FIG. 238 is a right side elevational view corresponding to FIG. 232;
FIG. 239 is a perspective view of a thirty fifth embodiment of a back pack with the text of SAN FRANCISCO, showing our new design;
FIG. 240 is a front elevational view corresponding to FIG. 239;

FIG. 241 is a rear elevational view corresponding to FIG. 239;
FIG. 242 is a bottom elevational view corresponding to FIG. 239;
FIG. 243 is a top elevational view corresponding to FIG. 239;
FIG. 244 is a left side elevational view corresponding to FIG. 239;
FIG. 245 is a right side elevational view corresponding to FIG. 239;
FIG. 246 is a perspective view of a thirty sixth embodiment of a back pack with the text of SEATTLE CITY, showing our new design;
FIG. 247 is a front elevational view corresponding to FIG. 246;
FIG. 248 is a rear elevational view corresponding to FIG. 246;
FIG. 249 is a bottom elevational view corresponding to FIG. 246;
FIG. 250 is a top elevational view corresponding to FIG. 246;
FIG. 251 is a left side elevational view corresponding to FIG. 246;
FIG. 252 is a right side elevational view corresponding to FIG. 246;
FIG. 253 is a perspective view of a thirty seventh of a back pack with the text of DON'T MESS WITH TEXAS, showing our new design;
FIG. 254 is a front elevational view corresponding to FIG. 253;
FIG. 255 is a rear elevational view corresponding to FIG. 253;
FIG. 256 is a bottom elevational view corresponding to FIG. 253;
FIG. 257 is a top elevational view corresponding to FIG. 253;
FIG. 258 is a left side elevational view corresponding to FIG. 253;
FIG. 259 is a right side elevational view corresponding to FIG. 253;
FIG. 260 is a perspective view of a thirty eighth embodiment of a back pack with the text of WASHINGTON, DC, showing our new design;
FIG. 261 is a front elevational view corresponding to FIG. 254;
FIG. 262 is a rear elevational view corresponding to FIG. 254;
FIG. 263 is a bottom elevational view corresponding to FIG. 254;
FIG. 264 is a top elevational view corresponding to FIG. 254;
FIG. 265 is a left side elevational view corresponding to FIG. 254; and,
FIG. 266 is a right side elevational view corresponding to FIG. 254.
The dashed broken lines in the figures depict stitching, a handle, straps, tags, pulls for zippers and portions of the article and form no part of the claimed design.
The dotted broken lines on the sides, top and bottom denote lettering and form no part of the claimed design.
